PERFUME DISPENSING IMPLEMENT

Mary Mildred Alexander, Los Angeles, Calif.

Application April 24, 1951, Serial No. 222,558

4 Claims. (Cl. 299—90)

1

This invention relates to a perfume dispensing device, embodied in an attractive novelty capable of being conveniently carried about and operable to deliver a perfume impregnated liquid spray.

One object of the invention is to provide a device which is a more conveniently manually operable implement to cause a spray of perfume impregnated liquid to be directed against any fabric or other object to be perfumed.

Another object is to provide, in a perfuming implement having in it a perfume reservoir, improved refilling means for said reservoir.

A more specific object is to provide a perfume dispenser which as to its external appearance resembles a miniature parasol, the ejecting of the perfume being accomplished by swinging the ribbed portions of the parasol-like article into a closer or more nearly collapsed relation to each other.

Other objects, advantages and features of invention will hereinafter appear.

Referring to the accompanying drawing which illustrates a preferred embodiment of the invention,

Fig. 1 is a view showing the article in vertical midsection except that some parts near the plane of section are shown in elevation. Linkage back of the plane of section is omitted to simplify the view. Broken lines indicate the position of parts when the article is in a more expanded condition.

Fig. 2 is an enlarged sectional detail, looking up from the horizontal plane indicated by line 2—2 on Fig. 1.

Fig. 3 is a side elevation, on a smaller scale than Figs. 1 and 2, showing the device in a moderately expanded condition.

Fig. 4 is a bottom plan view, the observer looking up approximately from line 4—4 on Fig. 3.

Fig. 5 is a bottom plan of the device in a more nearly collapsed condition than in Fig. 1, the viewpoint of the observer being approximately indicated by line 5—5 on the latter view.

Referring in detail to the drawing, the external parasol like side wall portion 7 consists of a suitable sheet material and is internally supported by a plurality of slightly arcuate moderately rigid stays 8. This structure surrounds a tubular axial shaft 9 carrying at one end a spraying nozzle 10 and at its opposite end being semicircularly curved as a handle portion 11.

A collapsible fluid tight bag 12 is shown concentrically surrounding said shaft 9, said bag being shown as made of sheet rubber or rubber like material. Adjacent to the aforesaid nozzle 10 a suitable liquid sealing means 13 is shown

between said bag and the tubular shaft 9, and a like sealing means 14 is shown between the opposite end portion of said bag and the shaft.

A parasol like foldable linkage 15 is shown occupying the moderately expanded lower end portion of the device as it appears in Fig. 1, this linkage being at its center pivotally connected to radial flanges 16a of a collar 16 slidably surrounding the shaft 9 and being, in a radially outwardly spaced relation to said flanges, pivotally connected to clips 17, each aforesaid arcuate stay 8 carrying one of these clips. Said linkage consists of a circumferentially arranged series of paired links, the links of each pair being swingably connected by pivot rivets 20. A ring carrying pull cord 21 is shown in Fig. 1 connected with the slidable collar 16 to aid the operator to expand the parasol like structure by pulling outwardly upon the said cord. An arm extension 15a is formed on the outer member of said linkage 15 and extends outwardly past the pivot 20 to form a stop means for said linkage when in an extended condition.

The extremity of the handle forming part 11 of the tubular shaft is provided with a closure plug 22 and adjacent to said tube with a check valve 23. Said tubular shaft also has, within the bag 12, ports 25 through which the perfume impregnated liquid 26 is supplied to said bag.

It will be seen that the bag 12 is considerably spaced away from that end of the shaft 9 which carries the handle 11, so that a working clearance is provided for the linkage 15 within the open end portion of the collapsible wall portion 7 of the device.

It will also be observed that the linkage 15 differs from the series of rods that hold the covering of a parasol in the expanded condition, each rod of the parasol being replaced by a pair of links wherein the links of the pair are pivoted to each other, one link being pivoted to the slideable collar 16 and the other link of the pair being pivotally related to the adjacent cover stay 8. This structure, being more compact than the conventional rod structure which it displaces, can be housed in that part of the space within the covering which is not occupied by the bag 12 when the device is partly collapsed, as shown in Fig. 1.

In the operation of the device the user will collapse its wall portion 7 by degrees thus from time, in turn, collapsing or contracting the elastic liquid container 12, each collapsing operation being performed in a sufficiently rapid manner to cause a spray 27 of the liquid perfume to issue from the nozzle 10, it being understood that at such times

said nozzle will be placed close to and directed toward the object or portion of the user's body to be perfumed.

When it is desired to refill the bag 12 the plug 22 will be removed and the ball check valve will be held open so that a fresh supply of the liquid perfume 26 may be forced into the bag through the tube passing from said tube into the bag through the ports 25. This refilling operation should be performed while the device is in the upstanding position shown in Fig. 1, and may be aided by the operator giving a downward pull upon the ring carrying cord 21, so as to aid in expanding the device.

I claim:

1. In a perfume dispenser, a parasol like structure comprising a tubular axial shaft provided with a spraying nozzle at one end and a handle at its opposite end and with a collapsible side wall portion surrounding said shaft, an elastic bag containing perfuming fluid and surrounding said tubular shaft in a fluid dispensing communication therewith, said bag being deflated and ejecting the perfume through said nozzle when said side wall portion is forcibly collapsed against the bag.

2. The structure set forth in claim 1, and said bag being spaced away from said handle, a collar slidably carried by said shaft in the space provided by the aforesaid spacing away of said bag from said handle, and a circumferentially extending series of paired pivoted together links in said space arranged around said shaft and connecting said collar with the wall portion of the parasol like structure.

3. In a device of the kind described, an elongated, fluid impervious collapsible bag to contain perfume in a fluid form, a tubular shaft extending axially through said bag in fluid com-

5
10
15

munication therewith and having end portions outside thereof, said bag being sealed in a fluid tight manner around said shaft at the places where the latter pass through the bag, one of the end portions of said shaft having outlet means for the perfume and the opposite end portion of said shaft having a filling opening, and a parasol like collapsible cover structure concentrically surrounding said bag and collapsible thereagainst to cause perfume to issue from said outlet means.

4. The structure set forth in claim 3, and that end portion of said shaft which is provided with the filling opening projecting considerably from said bag and being surrounded with the flared part of the parasol like covering, stays of the conventional parasol type secured to said covering, a slideable collar carried by said shaft within said flared portion of said covering, and pairs of links arranged in a circumferentially extending series around said shaft, the links of each pair being pivoted to each other, and in each pair one link being pivotally connected with said collar and the other link being in a connected pivotal relation to an adjacent aforesaid stay of the surrounding covering, and stop means to limit the extended movement of said links.

MARY MILDRED ALEXANDER.
